(57) **CLAIM**

I claim the design for a fish themed barbecue grill, as shown and described.

DESCRIPTION

FIG. 1 is a left side isometric view of a fish themed barbecue grill showing my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines are for illustrative purposes only and form no part of the claimed design.
